Term of patent 14 years

Int. Cl. D25—99

U.S. Cl. D13—1

FIG. 1

FIG. 2

FIG. 3

FIG. 4

FIGURE 1 is a front perspective view showing my new design of a pedestal base having a diving board operatively mounted thereon as shown in dotted delineation;

FIGURE 2 is a side elevational view thereof;

FIGURE 3 is a top plan view thereof; and

FIGURE 4 is an elevational view as seen from either end of my new pedestal base.

The diving board in dotted lines on the several views is for illustrative purposes only and forms no part of the claim.

I claim:

The ornamental design for a pedestal base, as shown and described.
